EDWIN J. TOOF, OF NEW HAVEN, CONNECTICUT.

SEWING-MACHINE.

No. 869,112.

Specification of Letters Patent.

Patented Oct. 22, 1907.

Application filed January 5, 1907. Serial No. 350,897.

To all whom it may concern:

Be it known that I, EDWIN J. TOOF, a citizen of the United States, and a resident of New Haven, in the county of New Haven and State of Connecticut, have 5 invented certain new and useful Improvements in Sewing-Machines, of which the following is a specification.

This invention relates to improvements in sewing machines of the rotary looper class, and is in the nature of an improvement upon that made the subject-matter 10 of an application filed by William M. Ammerman, October 22, 1904, Serial No. 229,628.

In the machine of the aforesaid application a rotary looper having a contained bobbin-case and bobbin is detachably connected to a rotary driver at the under 15 side of the sewing machine bed-plate, the said looper and bobbin-case both being open at their rear side to permit of the insertion and removal of a bobbin to and from a position within the bobbin-case upon the removal of the looper from connection with its driver and 20 the said bobbin-case being provided at its front side with an opening for the insertion of the operator's finger in ejecting the bobbin from the bobbin-case upon such removal of the looper from its driver. It has been found desirable, however, that said opening in the front 25 wall of the bobbin-case should also be capable of being utilized for the insertion of the operator's finger in conveniently and firmly grasping the looper and bobbin-case in effecting the disconnection of the same from the looper driver; such use of said opening in the machine 30 of the aforesaid application not having been readily permissible for the reason that a so-called "bobbin-retainer" carried by the looper driver in a position for engagement with the bobbin at its rear side operated to hold the bobbin in such close relation to the opening 35 in the front wall of the bobbin-case as to prevent the entry of the operator's finger through said opening until subsequent to a partial outward withdrawal of the looper and bobbin-case from connection with the looper driver and until after a preliminary or initial grasping 40 of the looper in effecting such partial withdrawal of the same.

It has therefore been one of the main objects of my present invention to provide a means whereby the operator may be permitted to enter a finger into the opening in the front wall of the bobbin-case upon taking initial hold of the looper and bobbin-case preparatory to withdrawing them from connection with the looper-driver.

In carrying my invention into effect I provide a 50 means for increasing the distance between the front wall of the bobbin-case, which constitutes one bobbin-retainer, and the oppositely located bobbin-retainer attached to the looper-driver, preliminary to the operator's grasping the looper and bobbin-case for the purpose 55 of withdrawing them from connection with the looper-driver, whereby space may be provided for the

entry of the operator's finger into the said opening in the front wall of the bobbin-case in grasping the same. Such increase in distance between the oppositely located bobbin-retainers is provided by rendering either 60 one or both of the retainers movable with respect to the other in a direction to vary the bobbin containing space therebetween; a means for rendering the retainers so movable being illustrated in the accompanying drawings forming part of this specification and set forth in 65 the detailed description which follows.

Referring now to the drawings, Figure 1 is a front end elevation of a rotary looper and associated parts embodying my invention, together with a portion of a hanger at the under side of the sewing machine bed-plate in 70 which the looper driver is journaled at its forward end. Fig. 2 is a front end elevation of the looper-driver with the looper and its contained parts disconnected therefrom. Fig. 3 is a longitudinal sectional elevation through the looper, looper-driver, and associated parts, 75 with the looper in locked connection with its driver. Fig. 4 is a similar view with the looper partially withdrawn from connection with its driver and with the distance between the bobbin-retainers sufficiently increased to permit of the entry of the operator's finger 80 through the opening in the front wall of the bobbin-case for gripping engagement with the latter. Figs. 5 and 6 are views similar to Figs. 3 and 4 showing a different embodiment of my invention.

In the drawings, 40 indicates a portion of a hanger at 85 the under side of the sewing machine bed-plate in which is journaled a rotary driving shaft 13 having attached to its front end a head or disk 18 in the face side of which is formed an open socket 19 adapted to receive the attaching shank of a looper, the said shaft 13 with its 90 attached head or disk 18 constituting a looper driver. The looper shown in the present case for connection with the said driver is what is commonly known as a hook and comprises a body portion 2 having a loop-seizing beak 3 and a central opening or chamber 4 for 95 the reception of a bobbin-case 5, which latter is retained in operative connection with the hook in the usual manner by means of a peripheral flange 6 thereon extending into a race-way groove 7 in the wall of the said hook chamber 4 and is held in a non-rotary position 100 with respect to the hook by means of an arm 8 thereon loosely engaging a coöperating part on the needle-plate (not shown).

The hook is provided at its rear side with a tubular shank 20 as a means for effecting connection with the 105 driver disk 18, the said shank being adapted to be inserted into the open socket 19 of the said driver disk and be removably retained therein by a suitable locking means, such means in the present case comprising a locking-lever 24 which is pivoted at 24' on the rear side 110 of the driver disk and arranged with one end 25 normally extending through a slot 18" in the driver disk to

a position for locking engagement with the hook shank 20 in a slot 27 therein and its opposite or operating end 28 extending to a convenient position to be reached by the operator adjacent to the periphery of the disk. In 5 placing the hook in operative connection with its driver, the beveled end 20' of the hook shank 20 in being entered into the driver socket will engage with the inwardly projecting end 25 of the locking-lever 24 and force the same laterally outward whereby it will ride 10 upon the outer surface of the shank until the slot 27 in the latter has been brought into registry with it, at which time the lever will automatically snap into the said slot under the action of a suitable spring, such as indicated at 30, and so operate to lock the hook in connection 15 with the driver. To unlock the hook preparatory to its disconnection from the driver, it is only necessary for the operator to press inwardly upon the face end of the locking lever, which operation removes its inner or locking end from locking position in the slot 27 20 of the hook shank.

In view of the detachable connection of the hook with its driver in the manner described, the usual bobbin-retainer latch at the front side of the bobbin-case is dispensed with. This is permitted by making both the 25 hook and the bobbin-case open at their rear side in a position registering with the opening through the tubular attaching shank 20 of the hook whereby the bobbin, indicated at 11, may be entered to or removed from its position in the bobbin-case at the rear side of the hook. 30 With this construction of hook and bobbin-case, the latter will preferably be provided with an inwardly turned bobbin-retaining flange or wall 12 for engagement with the bobbin at the front side thereof and suitable means will also be provided for engagement with 35 the bobbin at its rear side so as to retain the same in operative position in the bobbin-case after the hook has been connected with its driver. The means herein shown for so engaging with the bobbin at its rear side comprises a retainer in the form of a screw 14 having a 40 longitudinally adjustable screw-threaded connection with the hook driver at the center of its socket 19. An important feature of this retainer is the fact that it may be adjusted relatively to the bobbin-retaining wall 12 at the front side of the bobbin-case so as to vary the 45 space between the same to accommodate bobbins of different lengths or sizes and also provide the proper clearance space between the said retainer and the adjacent end of the bobbin for the passage of the inner side of the needle-thread loop when the latter is being carried 50 around the bobbin by the hook in the usual manner.

The construction and operation of parts thus far described is the same as that of the aforesaid application, and I will now proceed to describe my improvements as embodied in connection therewith. The operator, 55 in disconnecting the looper and bobbin-case from the looper-driver in the manner heretofore accomplished, grasps the looper at opposite sides thereof between the thumb and finger and with the thumb in position for pressing the lever 24 inwardly to release the looper, 60 after which releasing operation is effected the operator withdraws the looper and contained parts from connection with the looper-driver and then ejects the bobbin from the bobbin-case by the entry of the finger through the opening 12' in the front of the bobbin-case. It is 65 desirable however, as hereinbefore stated, that the op-

erator may be permitted to enter a finger into said opening 12' in the front wall of the bobbin-case for the purpose of conveniently and firmly grasping the same preparatory to disconnecting the looper and bobbin-case from the looper-driver, and this may be permitted by 70 increasing the distance between the retainers at opposite sides of the bobbin preliminary to the operator's grasping the looper for the purpose of disconnecting it from its driver. One means for effecting such preliminary increase of distance between the retainers, as 75 shown in Figs. 2, 3 and 4, comprises a spring 50 secured at one end to the inner wall of the driver socket 19, as by means of a screw 51, with its opposite or free end arranged in position to engage the rear end of the looper shank 20; the said spring being operative upon the release of the looper by its locking lever 24 to automatically project the looper and its contained bobbin-case forward a sufficient distance from the driver and the retainer 14 supported thereby as to provide sufficient room for the entry of the operator's finger through the 80 opening 12' in the front of the bobbin-case, as shown in Fig. 4, whereby the operator may firmly grasp the bobbin-case and looper preparatory to withdrawing them from connection with the looper driver. By making the spring 50 of sufficient strength, it may also be utilized, if so desired, to automatically effect the complete ejection of the looper and bobbin-case from connection with the looper-driver upon the release of the looper by the locking lever 24.

In Figs. 5 and 6 I have shown another means for increasing the distance between the oppositely-located bobbin-retainers preliminary to grasping the looper and bobbin-case for effecting their withdrawal from connection with the looper-driver, which consists in movably supporting the retainer 14 in its normal operative bobbin-retaining position in a manner to permit of its being moved backward or in a direction away from the front bobbin-retainer 12, such backward movement being conveniently accomplished by the operator engaging the bobbin through the opening in the front of the bobbin-case and pressing it backwardly against the said retainer, in manner as clearly shown in Fig. 6. The means shown in the present case for so supporting the retainer 14 comprises a head 60 slidably supported within a counter-part opening in the forward end of the 100 driver shaft 13 and carrying at its front end the retainer 14, the said head being limited in its movement within the shaft 13 by means of a pin 61 thereon operating within a longitudinal slot 62 in the shaft 13, and being 105 yieldingly held in its normal operative position with the said pin 61 at the forward end of the slot 62, as shown in Fig. 5, by means of a coiled spring 63 expanding between a shoulder 64 on the head 60 and the inner end wall of the opening in the shaft 13. As a means for maintaining the adjustability of the retainer 14 with 110 respect to the front retainer 12, it has a screw-threaded connection with the head 60 in the same manner as it does with the driver shaft direct in the construction shown in Figs. 3 and 4.

What I claim is:

1. In a sewing machine, the combination of a rotary looper and a bobbin-case and bobbin contained within said looper, the said bobbin-case being open at one side for the insertion and removal of a bobbin and being provided at its opposite side with a finger-receiving opening, and bobbin-retainers for engaging a bobbin within the bobbin-case 130

at opposite sides thereof, one of said retainers being spring-controlled for endwise movement relatively to the other, for the purpose set forth.

2. In a sewing machine, the combination of a rotary looper and a bobbin-case and bobbin contained within said looper, the said looper and bobbin-case both being open at one side for the insertion and removal of a bobbin to and from a position within the bobbin-case and the said bobbin-case being provided at its opposite end with a bobbin retainer and with a finger-receiving opening, and a bobbin retainer at that side of the bobbin opposite the first-mentioned retainer and being coöperative with the latter to hold the bobbin against undue endwise movement therebetween, one of said retainers being spring-controlled for endwise movement relatively to the other, for the purpose set forth.

3. In a sewing machine, the combination of a rotary looper and a bobbin-case and bobbin contained within said looper, the said looper and bobbin-case both being open at their rear side for the insertion and removal of a bobbin to and from a position within the bobbin-case and the said bobbin-case being provided at its front side with a bobbin-retainer and with a finger receiving opening, and a bobbin-retainer at the rear side of the bobbin coöperative with the first mentioned bobbin-retainer to hold the bobbin against undue endwise movement therebetween, one of said retainers being spring-controlled for endwise movement relatively to the other, for the purpose set forth.

4. In a sewing machine, the combination of a rotary looper and a bobbin-case and bobbin contained within said looper, the said looper and bobbin-case both being open at their rear side for the insertion and removal of a bobbin to and from a position within the bobbin-case and the said bobbin-case being provided at its front side with a bobbin-retainer and with a finger-receiving opening, and a bobbin-retainer supported independent of the bobbin-case at the rear side of the bobbin and being coöperative with the first mentioned bobbin-retainer to hold the bobbin against undue endwise movement therebetween, one of said retainers being spring-controlled for endwise movement relatively to the other, for the purpose set forth.

5. In a sewing machine, the combination with a rotary looper-driver, of a looper detachably connected with said

driver and having a bobbin-case and bobbin supported therein, the said looper and bobbin-case both being open at their rear side for the insertion and removal of the bobbin to and from a position within the bobbin-case and the said bobbin-case being provided at its front side with a bobbin-retainer and with a finger-receiving opening, and a bobbin-retainer carried by the looper-driver in position at the rear side of the bobbin and being coöperative with the first mentioned bobbin-retainer to hold the bobbin therebetween, one of said retainers being spring-controlled for endwise movement relatively to the other, for the purpose set forth.

6. In a sewing machine, the combination with a rotary looper-driver, of a looper detachably connected with said driver and having a bobbin-case and bobbin supported therein, the said looper and bobbin-case both being open at their rear side for the insertion and removal of the bobbin to and from a position within the bobbin-case and the said bobbin-case being provided at its front side with a bobbin-retainer and with a finger-receiving opening, and a bobbin-retainer carried by the looper-driver in position at the rear side of the bobbin and being coöperative with the first mentioned bobbin-retainer to hold the bobbin therebetween, locking means for detachably holding the looper and its supported bobbin-case and bobbin in connection with the looper-driver, and means for automatically moving the looper and bobbin-case in a direction outwardly from the driver-supported-bobbin-retainer upon the release of the looper by its locking means, for the purpose set forth.

7. In a sewing machine, the combination of a rotary looper-driver, a looper supporting a bobbin-case and bobbin and having a shank slidably connected with said driver, locking means for detachably holding the looper in connection with its driver, and means for automatically disconnecting the looper from the driver upon the release of the looper by its locking means.

Signed at New York, in the county of New York, and State of New York, this 26th day of December, A. D. 1906.

EDWIN J. TOOF.
